United States Patent Office

Des. 203,733
Patented Feb. 8, 1966

203,733

ASH TRAY

Miriam I. Aubry, 643 Salem St., North Andover, Mass.

Filed Aug. 5, 1965, Ser. No. 86,464

Term of patent 7 years

(Cl. D85—2)

FIG. 1

FIG. 2

FIG. 3

FIG. 4

FIG. 5

FIG. 1 is a perspective view of an ash tray showing my new design;

FIG. 2 is an end elevation thereof;

FIG. 3 is an end elevation view taken from the opposite side of view shown in FIG. 2;

FIG. 4 is a top plan view; and

FIG. 5 is a bottom plan view.

I claim:

The ornamental design for an ash tray, as shown.
